UNITED STATES PATENT OFFICE

VIRGILE PROVOST, OF COHOES, NEW YORK

CHAIN CONNECTION

Application filed October 22, 1931. Serial No. 570,464.

This invention relates to tie plates particularly for coupling chains and specifically for coupling tire chains, that is, the stringer and cross chains which make up the tire chain for 5 automobiles. It will be understood, however, that this disclosure is illustrative and in no sense restrictive, and that the tie plate may be utilized to join chains other than the tire chain in connection with which it is shown 10 and described.

The purpose of the invention is to provide a tie plate of simple and rugged construction which may be readily applied to the chains to be connected and in the use of which the 15 stringer chains and cross chains will be maintained always in proper relation, and the cross chains may be readily applied or removed when, by reason of breakage or wear, it is necessary to renew them.

20 In the drawing herewith is shown one physical embodiment of my invention, and that the best now known to me.

In the drawing:

25 Figure 1 is a view of so much of the stringer chain and cross chain coupled by my improved tie plate as is necessary to illustrate the invention.

30 Figure 2 is a sectional view on substantially the line 2—2 of Figure 1, looking in the direction of the arrows.

Figure 3 is an end view looking from the right of the tie plate.

35 Figure 4 is a perspective view of the tie plate shown in the other figures.

Figure 5 is a perspective view of a slightly modified form of tie plate.

40 Referring to the drawing by numbers, like numbers indicating like parts in the several views, 10 indicates the stringer chain of any usual or desired construction and 11 indicates the cross chain of a not unusual type.

The tie plate has a body portion 12 terminating at one end in an eye 13 and at the other end in a hook made up of a shank portion 14 and a bill 15 so as to provide a receiving hook 45 for a link of the cross chain 11.

The eye 13, as shown particularly in Figure 2, is substantially triangular in cross section, its rear wall being disposed at an abrupt angle, here shown as an acute angle, to the

body portion 12 of the tie plate with the forward end of the eye bent downwardly so as to provide a substantially triangular orifice to form the eye. The purpose of this construction is two-fold. First, the link of the 55 stringer chain 10, which is engaged by the eye, will, by reason of the angular relation of the rear wall of the eye to the body portion of the tie plate, be held always at the lowest point in the angle when under strain, 60 so as to give a direct pull between the chain 10 and the tie plate 12 as nearly along the longitudinal axis of the tie plate as is practical, and danger of opening the eye under undue strain which is likely to occur where 65 the point of stress is away from the body portion of the tie plate, is eliminated. Second, the forward portion of the eye when bent downward into proximity to the body of the tie plate serves to clamp and hold in position the resilient member 16, here shown as a flat spring plate secured to the body portion 12 of the tie plate, and which will now be 70 described.

It is desirable, of course, and broadly 75 speaking it is common, to use a resilient member to hold the link of the cross chain in the hook, but in many of the devices now known to me, no attempt has been made to maintain the link always in the same relative position 80 in the bight of the hook so as to insure the strain coming always at one point and avoid the shifting of the link in the bight and consequent application of the strain at different 85 points.

As here shown, the resilient member 16 is a flat spring secured in any suitable manner to the body portion of the tie plate 12, one convenient manner here shown being by means of a punching 17 in the body of the 90 tie plate adapted to engage an opening 18 in the resilient member 16, and as shown in Figure 2, be headed down to secure the resilient member 16 in place. Preferably the punching 17 will be angular in cross section, 95 here being shown as square, in order to prevent pivotal shifting of the plate of the resilient member 16 relative to the tie plate. Further to guard against pivotal shifting of the resilient member 16, its rear end abuts the 100

rear wall of the eye 13, here shown as formed square, so as to resist any tendency of the resilient member 16 to shift pivotally. Furthermore, as is shown more particularly in Figure 2, the forward end of the eye when bent down in the act of assembling the parts from the dotted position shown in Figure 2 to the full line position, is clamped closely down against the resilient member 16 so as to further lock such member in place and additionally guard against any shifting of the plate.

It will be noted in Figure 1, and in dotted lines in Figures 4 and 5, that the resilient member 16 at its forward end substantially spans the bight of the hook from the bill 15 to the shank portion 14 thereof. This positioning of the resilient member or spring plate 16 forms an enclosure for the link of the cross chain 11 which is in engagement with the hook and prevents that link from shifting back away from the bight of the hook, so that the parts are held in snug normal position as distinguished from constructions in which the spring retaining member does not span the bight of the hook, but merely guards the bill of the hook, leaving the entire hook aperture open for play of the link.

In order that the links of the cross chain 11, which are commonly fashioned in a figure-8 formation, may lie in a natural position relative to the hook portion of the tie plate and each other, and prevent any distorting strain on the end link of the cross chain, I preferably provide the hook between the bight and the end thereof with seats or depressions 19 on each side of the hook and offset on each side of the longitudinal center thereof so that, as shown in Figure 3, the limbs of the cross chain link 11 will lie within the seats 19 and in a normal undistorted position. The seats 19 may be formed in any desired way, but preferably, and as here shown, will be formed by bending the end of the hook, as clearly illustrated in Figures 1, 2, 3, and 4, this bend being graduated from the end of the hook to the bight of the hook from maximum to zero. Such conformation gives a true seat for the ends of a link of the cross chain 11 and permits the link to take a normal position relative to the succeeding links in the chain.

In assembling the parts it will be understood that the resilient member or spring plate will be positioned on the tie plate, the securing means, as for example the punched lug 17 or other equivalent fastening means riveted down, the eye 13 may be partially bent to form the rear wall, hooked over the link of the stringer chain 10 with which it is to be connected, and then the forward end of the eye will be bent downwardly to enclose the link and engage the rear end of

the resilient member or spring plate with a clamping action.

With the parts thus assembled the cross chain may readily be snapped into the hook by engaging the end of the link with the spring plate adjacent the bill of the hook and then by a half turn or twist of the link of the cross chain against the spring plate, it may be engaged with the hook and brought to the position shown in Figure 1. The removal of the cross chain 11 for renewal, repair, or adjustment may be readily made by forcing the link against the end of the spring plate and past the bill of the hook, the relation of the bill of the hook and the end of the spring plate being such as to facilitate the engagement and disengagement of the cross chain link.

While this is the preferred embodiment of my invention, it will be understood that the hook portion may be formed without these seats but embodying the other features of novelty, as shown in Figure 5.

It will be understood that such changes in mechanical make-up from the disclosure herein may be made as are within the skill of the mechanic and still remain within the purview of my invention.

I claim:

1. A chain tie plate having an eye, the rear wall of which is at an abrupt angle to the plate.
2. A chain tie plate having an eye, the rear wall of which is at an acute angle to the plate.
3. A chain tie plate having an eye substantially triangular in cross section.
4. A chain tie plate having a hook member, and a flat resilient holding member secured and contiguous to said plate and so disposed as to prevent a part engaged by the hook from moving out of the bight of the hook.
5. A chain tie plate having a hook member and a flat resilient holding member secured and contiguous to said plate with its end substantially spanning said hook from its bill to its shank to prevent a part engaged by the hook from moving out of the bight of the hook.
6. A chain tie plate having a hook at one end, an eye at the opposite end, and a resilient hook closing member, the rear end of which abuts the rear wall of said eye to prevent pivotal shifting of said resilient member, the forward wall of said eye being bent downwardly into clamping engagement with said resilient member.
7. A chain tie plate having a hook at one end, an eye at the opposite end, and a flat hook closing spring secured to said plate with its rear end abutting the rear wall of said eye to prevent pivotal shifting of said spring, the forward wall of said eye being bent downwardly into clamping engagement with said spring.

8. A chain tie plate having a hook at one end, an eye at the opposite end, and a flat hook closing spring secured to said plate, the rear end of which spring abuts the rear wall of said eye to prevent pivotal movement of said spring, the forward end of said spring substantially spanning the hook from its bill to its shank to prevent a part engaged by the hook from moving out of the bight of the hook.
9. A chain tie plate having a hook provided on opposite sides with offcentered seats to receive the limbs of a hook-engaged link.
10. A chain tie plate having a hook bent in opposite directions longitudinally to form offcentered seats on opposite sides to receive the limbs of a hook-engaged link.
11. A chain tie plate having a hook provided with offcentered seats on opposite sides inclined from the bight of the hook toward its end.
12. A chain tie plate having a hook bent to form offcentered seats on opposite sides inclined from the bight of the hook toward the end to receive the limbs of a hook-engaged link.
13. A chain tie plate having a hook bent to form offcentered seats on opposite sides inclined from the bight of the hook toward the end to receive the limbs of a hook-engaged link, said seats being inclined from the bight of the hook toward its end.
14. A chain tie plate having a hook bent to form offcentered seats on opposite sides inclined from the bight of the hook toward the end to receive the limbs of a hook-engaged link, said seats being inclined and flared outwardly from the bight of the hook toward its end.
15. In a chain tie plate, means permanently to attach said plate to a stringer chain, said means comprising a substantially triangularly shaped closed eye at one end of the plate, a hook member for attachment to a cross chain at the other end of the plate and provided with means to prevent distortion of the cross chain, and means secured to the plate to prevent disengagement of the cross chain from the hook.
- 50 In testimony whereof I affix my signature.

VIRGILE PROVOST.
